ATTORNEYS.

UNITED STATES PATENT OFFICE.

THOMAS ALLSOP AND HARRY H. WIGGLESWORTH, OF PHILADELPHIA, PENNSYLVANIA, ASSIGNORS TO THE PHILADELPHIA DRYING MACHINERY COMPANY, OF PHILADELPHIA, PENNSYLVANIA, A CORPORATION OF PENNSYLVANIA.

DRYING MACHINE.

Original application filed May 13, 1924, Serial No. 712,976. Divided and this application filed March 8, 1926. Serial No. 92,985.

This invention relates to drying machines and the subject-matter thereof is a division from our co-pending application for patent, Serial Number 712,976, filed the 13th day of May, 1924. More specifically the substance of the present case is directed to machines adapted for progressing rows of aligned form carriers through a drying enclosure by means of intermittently actuated endless conveyors.

The primary object of the present improvements is to provide a novel form of drying enclosure sub-divided to afford superposed compartments with a subjacent passage-way, whereby the drying medium is caused to traverse said enclosure with looped directional flow.

Other objects and attendant advantages will be apparent from the following detailed explanation of a typical embodiment of our invention, as illustrated in the accompanying sheets of drawings, and succinctly defined as to features of novelty—as well as scope—by the subjoined claims.

In the drawings:

Fig. I is a plan view of a hosiery drying machine embodying this invention, parts being broken away—or in section—to more clearly illustrate certain underlying features.

Fig. II is a vertical section, taken approximately on the plane indicated by the arrows II—II in Fig. I; and,

Fig. III is a view in elevation, at the feeding-in end of the machine, with a portion of the upper enclosing shell broken away to disclose certain underlying parts.

The machine herein illustrated and to which our invention has been, for convenience, specifically applied, comprises a frame work of standard section verticals 4, braced by similar section transverse members 5, closed-in by thermo-insulated plates 6, to afford upper and lower compartments 7, 8, through which rows of aligned forms 9 are intermittently progressed by endless chain conveyors 10; and an air passage 11, by way of which a vertically rotatable fan 12, circulates the drying medium with looped directional flow, as indicated by the arrows shown on Fig. III. The aforesaid compartments 7,

8, and air passage 11 are conveniently, though not essentially, rectangular in transverse section, while the former 7 is subdivided by spaced vertical partitions 13 with an attached diaphragm 14. It is also observable that the lower compartment 8 extends laterally to the front and rear of the machine to provide "boarding" and "stripping" stations "B", "S", respectively, whereat operatives are located to apply the wet articles to be dried by progression through the machine, and to remove the same after drying. Furthermore, the front and rear walls 15, 16, of the upper compartment 7, are provided with ingress and egress openings 17, 18, respectively, of appropriate configuration to permit free passage for the successive rows of clothed forms 9, as will be readily understood by those acquainted with the art to which our invention appertains.

Laterally across the upper portion of the compartment 7 are a plurality of radiator pipe banks 19—dividing said upper portion into parallel zones *a*, *b*, and *c*—through which the heating medium is circulated in accordance with well known practice. It is also noteworthy that the drying compartment 7 is transversely divided by a partition 20 affording upper and lower chambers with communicating slots 21 for the free passage of the forms 9; said partition and slots serving to define a looped-directional circulatory flow for the drying medium, as indicated by the arrows on Fig. III.

The endless chain conveyors 10 are threaded through the compartments 7, 8 over and under sprocket wheels 22, 23, respectively; as well as around relatively larger front and rear chain wheels 24, 25, as best indicated in Fig. II. The means effective to progress the chain conveyors 10 comprises a change gear including a toothed wheel 26 associated—or integral—with one of the sprocket wheels 22, meshing a gear 27, on a horizontal shaft 28, journaled in bearings 29, secured to the machine front wall 15. Conveniently splined on the outer end of the horizontal shaft 28 is a pinion 30 meshing with a gear 31, secured at one end of a second horizontal shaft 32, journaled in bearings 33 at the

front of the compartment 7. This second horizontal shaft 32, in turn, is rotated through the medium of an intermittent bevel-couple 34, by a vertical shaft 35 journaled in bearings 36, and said shaft is revolved by a worm drive 37 and belt transmission 38 from a countershaft—not shown—connected with any convenient source of power. Rotation of the fan 12 is also effected by a belt drive 39 from the aforementioned countershaft, as will be understood by anyone acquainted with the art. It is well to note that the hereinbefore referred to sprocket wheels 22 are attached on transverse shafts 40, journaled in bearings 41, at the sides of the compartment 7; whereas, the sprocket wheels 23 and chain wheels 24, 25 are supported by stub-shafts 42, in appropriate bearings 43, to afford free passage 20 for the forms 9 through the machine, as later on fully explained.

The means for supporting and progressing successive rows of aligned forms 9 are fully described in our previously referred to 25 co-pending application Serial Number 712,976, and for brevity herein will be but briefly explained. Each row of aligned forms 9 is carried by a T-section bar 44 having anti-friction end rollers 45 adapted 30 to traverse the guide-way tracks 46, best illustrated in Fig. II, means being provided to temporarily arrest and stabilize each successive row of said forms at the boarding station "B", as fully set forth in the above 35 cited application for patent.

An exhaust outlet or outlets 47 is, or are, provided in connection with the passage 11 to carry away the proper quantity of moisture-laden air, while an appropriate damper 40 control will—obviously—be associated therein so as to regulate the exhaust as desired.

The operation of our novel drying machine is briefly as follows:—

Assuming that an operative is located at 45 each station "B" and "S", and that motion is transmitted to the worm drive 37, the vertical shaft 35 will be rotated, and, by means of the bevel-couple 34 impart intermittent rotary motion to the horizontal shaft 32. 50 In turn this shaft 32, through the gears 31, 30, 27 and 26, will intermittently rotate the front transverse shaft 40, with consequential progression of the conveyor chains 10. If the shaft 40 is driven in a clock-wise direction—for example, the conveyor chains 10 will be traveled in the direction indicated by the arrows on Fig. II, and as a bar 44 is temporarily arrested at the station "B", the forms 9 thereon will be clothed with wet 55 hose by the operative. The following progressive movement of the conveyor chains 10 advances the bar 44 of clothed forms 9 along the guide-way tracks 46, through the ingress opening 17, into the first drying zone *a* of the compartment 7, replacing them at the

station "B" with a fresh row of stripped forms 9 for clothing. The conveyor chains 10, by subsequent intermittent movements, gradually progress the clothed forms 9, by stages, over a vertically undulate course 70 through the consecutive zones *a*, *b* and *c*, of the drying chamber 7 until a bar 44 of dried hose arrives at the egress opening 18. This intermittent progression of the rows of forms 9 through the drying compartment 7 75 will occupy sufficient time so that, when the forms 9 arrive at the egress opening 18, the hosiery thereon will be thoroughly dry. With the next progressive movement of the conveyor chains 10, the row of dried hose 80 is advanced to the station "S", whereat the operative will strip them from the forms 9. Attention is drawn to the fact that each track 46 at the station "S" is interrupted 85 at 48—Fig. II—and provided with an indent 49 functional as a pivot for the rollers 45, whereby the forms 9 automatically gravitate towards the operative stationed thereat to aid "stripping." Upon further movement the forms are reversely rocked as indicated at *x*, within the compartment 8, as will be understood by following the travel 90 of the conveyor chains 10 about the chain wheels 25, and the course of the rollers 45 over the indented parts 50 of the tracks 46. 95 Incidentally, it will be understood that the tracks 46 are interrupted, where necessary, to accommodate the illustrated flight of the conveyor chains 10 relative to the travel of the rollers 45 over said tracks.

From the foregoing it is thought that the advantages and novel features involved in our invention will be fully appreciated, while the looped circulatory flow of the heating medium relative to the rows of 105 aligned forms 9 is so apparent as not to require further explanation herein.

Having thus described our invention, we claim:—

1. A drying machine for textile articles including an enclosure having opposed lateral lower extensions, said enclosure being subdivided by a transverse slotted partition to afford upper and lower communicating compartments with the base thereof defining a sub-passage-way connecting the extensions, means subdividing the upper compartment into parallel drying zones, and means for circulating a drying medium through the upper and back through the lower compartments with looped directional flow.

2. A drying machine including an enclosure having opposed lower lateral extensions, said enclosure being subdivided by a transverse slotted diaphragm to afford superposed communicating compartments with the base thereof defining a sub-passage-way connecting the extensions, means for circulating a drying medium through said compartments with looped directional flow, and

radiating means dividing one of the compartments into parallel drying zones.

3. A drying machine including an enclosure having opposed lower lateral extensions, said enclosure being subdivided by a transverse slotted diaphragm to afford upper and lower communicating compartments with the bottom thereof defining a sub-passage-way alignedly connecting the extensions, means for circulating a drying medium transversely through said upper and lower compartments with looped directional flow, and radiator coils dividing the upper compartment into parallel drying zones.

4. A drying machine including an enclosure having opposed lower lateral extensions, said enclosure being subdivided by a transverse slotted diaphragm to afford upper and lower communicating compartments with the bottom thereof defining a sub-passage-way alignedly connecting the extensions, means for circulating a drying medium transversely through the upper and lower compartments with looped directional flow, radiators dividing the upper compartment into parallel drying zones, and means progressing successive rows of aligned drying

forms through the consecutive zones over a vertically-undulated relatively-reciprocating course.

5. A drying machine including an enclosure having opposed lower lateral extensions, said enclosure being subdivided by a transverse slotted diaphragm to afford upper and lower communicating compartments with the bottom thereof establishing a sub-passage-way alignedly connecting the extensions, means for circulating a drying medium transversely through the upper and lower compartments with looped directional flow, radiators dividing the upper compartment into parallel drying zones, and means progressing successive rows of aligned drying forms through the consecutive zones over a vertically-undulated relatively-reciprocating course with provision for forward inclination at stripping location and reverse inclination during retrogression through the sub-passage-way back to reclothing position.

In testimony whereof, we have hereunto signed our names at Philadelphia, Pennsylvania, this 2nd day of March, 1926.

THOMAS ALLSOP.

HARRY H. WIGGLESWORTH.
